UNITED STATES PATENT OFFICE

169,532

DRAWER PULL

James R. Deadrick, Winston-Salem, N. C., assignor to The Bassick Company, Bridgeport, Conn., a corporation of Connecticut

Application January 7, 1953, Serial No. 23,061

Term of patent 14 years

(Cl. D10—8)

To all whom it may concern:

Be it known that I, James R. Deadrick, a citizen of the United States, residing at Winston-Salem, in the county of Forsyth and State of North Carolina, have invented a new, original, and ornamental Design for a Drawer Pull, of which the following is a specification, reference being had to the accompanying drawing, forming a part thereof.

Fig. 1 is a front elevational view of a drawer pull showing my new design;

Fig. 2 is a rear elevational view;

Fig. 3 is a top plan view;

Fig. 4 is a bottom plan view;

Fig. 5 is a side elevation; and

Fig. 6 is a sectional view taken on the line 6—6 of Fig. 1.

I claim:

The ornamental design for a drawer pull, substantially as shown.

JAMES R. DEADRICK.
